US0D1021769S

(12) **United States Design Patent** (10) Patent No.: **US D1,021,769 S**
(45) Date of Patent: ** Apr. 9, 2024

(54) **BATTERY PACK**

(71) Applicants: **ESSENCE TECHNOLOGY HOLDINGS (HK) LIMITED**, Hong Kong (CN); **NEXIGHT INC**, Beaverton, OR (US)

(72) Inventor: **Dongwei Yang**, Hong Kong (CN)

(73) Assignees: **ESSENCE TECHNOLOGY HOLDINGS (HK) LIMITED**, Hong Kong (CN); **NEXIGHT INC**, Beaverton, OR (US)

(**) Term: **15 Years**

(21) Appl. No.: **29/824,964**

(22) Filed: **Jan. 28, 2022**

(30) **Foreign Application Priority Data**

Jan. 20, 2022 (CN) 202230040588.9

(51) LOC (14) Cl. **13-02**

(57) **CLAIM**

The ornamental design for a battery pack, as shown and described.

DESCRIPTION

FIG. 1 is a perspective view of a battery pack showing my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof in a usage state; and,

FIG. 10 is a perspective view thereof in another usage state. The broken lines in the drawings depict portions of the battery pack that form no part of the claimed design.

1 Claim, 10 Drawing Sheets
